The ornamental design of a single pole, angled power connector, as shown and described.

DESCRIPTION

FIG. 1 is a perspective of a single pole, angled power connector, showing our new design; FIG. 2 is a top plan view thereof;

FIG. 3 is a front elevation view thereof;

FIG. 4 is a right side elevation view thereof;

FIG. 5 is a back elevation view thereof;

FIG. 6 is a left side elevation view thereof; and,

FIG. 7 is a bottom plan view thereof.

The designations of the views below as top, bottom, right side, left side, front, and back are for ease of discussion only and are not intended to limit the single pole, angled power connector to one particular orientation. The single pole, angled power connector can be oriented in other directions which would alter these designations.
